CLAIM

The ornamental design for disk storage container, as shown and described.

DESCRIPTION

FIG. 1 is a perspective view of the disk storage container of the present invention;

FIG. 2 is a top plan view of FIG. 1;

FIG. 3 is a rear view of FIG. 2;

FIG. 4 is a front elevational view of FIG. 2;

FIG. 5 is a left side elevational view of FIG. 2;

FIG. 6 is a right side elevational view of FIG. 2;

FIG. 7 is a bottom plan view of FIG. 2;

FIG. 8 is a perspective view of a second embodiment of the disk storage container of FIG. 1;

FIG. 9 is a top plan view of the disk storage container of FIG. 8;

FIG. 10 is a rear view of FIG. 9;

FIG. 11 is a front elevational view of FIG. 9;

FIG. 12 is a left side elevational view of FIG. 9;

FIG. 13 is a right side elevational view of FIG. 9; and, FIG. 14 is a bottom plan view of FIG. 9.
